UNITED STATES PATENT OFFICE.

GRANVILLE H. GRAY, OF MARION, INDIANA, ASSIGNOR OF ONE-HALF TO
EMIL GERLACH, OF SAN FRANCISCO, CALIFORNIA.

DESIGN FOR A JAR-COVER.

SPECIFICATION forming part of Design No. 29,674, dated November 15, 1898.

Application filed October 12, 1898. Serial No. 693,349. Term of patent 14 years.

To all whom it may concern:

Be it known that I, GRANVILLE H. GRAY, a citizen of the United States, residing at Marion, in the county of Grant and State of Indiana, have invented and produced a certain new and original Design for a Jar-Cover, of which the following is a specification.

Figure 1 is a view in side elevation of a jar-cover showing my new design. Fig. 2 is a plan view of same, and Fig. 3 a sectional view taken on the line 3 3 of Fig. 2.

As shown in the drawings, the leading or material feature of my design consists of a circular disk or body portion A, having transversely grooved or corrugated edges B, as shown in Fig. 2, and an under side annular collar or flange C, with external screw-threads D, as shown in Figs. 1 and 3. The grooves

or corrugations B are at right angles to the flat top surface of the disk A. The top surface of the disk is ornamented by lowering the middle of it to form the concavity E. The collar or flange C has a groove C' around its lower edge.

Having described my invention, what I claim as new, and wish to secure by Letters Patent, is—

The design for a jar-cover, as herein shown and described.

In witness whereof I have hereunto set my hand and seal, at Marion, Indiana, this 20th day of September, A. D. 1898.

GRANVILLE H. GRAY. [L. S.]
